Primary Examiner — Lauren D McVey(74) *Attorney, Agent, or Firm* — Hanley Flight & Zimmerman LLC(57) **CLAIM**

The ornamental design for a large format printer, as shown and described.

DESCRIPTION

FIG. 1 is a left, front perspective view of a large format printer showing our new design;

FIG. 2 is a right, front perspective view of the printer of FIG. 1;

FIG. 3 is a front elevation view of the printer of FIG. 1; FIG. 4 is a right side elevation view of the printer of FIG. 1; and,

FIG. 5 is a left side elevation view of the printer of FIG. 1. The dashed broken lines show portions of the large format printer and surfaces adjacent the dashed broken lines that form no part of the claimed design.

The dotted broken lines that are immediately adjacent to the claimed areas and define broken line regions depict the bounds of the claimed design.

The dotted field bounded by dashed broken lines in FIGS. 1-3 represent a netting that forms no part of the claimed design.
